PATRICK SLEVIN, JOHN SLEVIN, AND FRANCIS SLEVIN, OF NEW YORK, N. Y.

Letters Patent No. 77,828, dated April 28, 1868.

WHISTLE.

The Schedule referred to in these Letters Patent and making part of the same.

TO ALL WHOM IT MAY CONCERN:

Be it known that we, PATRICK SLEVIN, JOHN SLEVIN, and FRANCIS SLEVIN, of the city, county, and State of New York, have invented a new and improved Whistle; and we do hereby declare that the following is a full, clear, and exact description thereof, which will enable those skilled in the art to make and use the same, reference being had to the accompanying drawings, forming part of this specification.

The present invention relates to that class of whistles in the sounding of which they are placed upon the tongue within the mouth, with the reed of the whistle next to the teeth; and the invention consists in making the holder for the reed of a bow-shape, and of any suitable material, with the reed secured to such bow around its edges in any proper manner, but left free or exposed at one edge to the action of the tongue, mouth, and lips, for producing the desired whistling sound.

In the accompanying plate of drawings our improved whistle is illustrated—

Figure 1 being a plan or top view of the same,

Figure 2 a section taken in the plane of the line x x , fig. 1, and

Figures 3 and 4 similar views to figs. 1 and 2, but of the old form of that class of whistles embraced in the present invention.

Similar letters of reference indicate corresponding parts.

A, in the drawings, represents the holder for the reed B to the whistle.

This holder A is made of a bow or curved shape, from end to end, and of India rubber, gutta percha, bone, wood, or any other suitable material.

The two ends C and side edges D to this holder A are grooved, and in them, by means of a metallic band, a, the reed B is secured with its side edge b free.

To use the whistle above described, place it on, with the reed next to the tongue within the mouth, and with the free edge of the reed next to the teeth, when, blowing gently, the movement of the tip of the tongue, of the mouth, and the quiver of the lips will produce a variety of notes and sounds that by practice can be made to resemble or imitate the sounds of a mocking or other bird.

In lieu of securing the reed to the holder in the manner above described, other ways may be employed, as, for instance, by making the bow or holder in two parts or sections hinged together, and closed upon opposite sides by clasps, screws, or other suitable means, or by clasping the reed upon the holder with metal or other suitable clasps, bent around the edges of the bow, or by tying it with a cord or other suitable means; and, therefore, we do not intend to limit ourselves to any particular mode or means of fastening, the invention consisting in the combination of the bow-shaped holder with a reed, made of any suitable material, such as gold-beater's skin, in a manner substantially as described.

It may be here observed that the reed, if so desired, may be hung to the holder or bow in such a manner that as one part has become worn it may be adjusted to bring another part of the reed in position for operation, as, for instance, by hanging the reed upon rollers.

We claim as new, and desire to secure by Letters Patent—

The combination of the bow-shaped holder and reed, substantially as and for the purpose described.
